UNITED STATES PATENT OFFICE

2,416,029

COSMETIC APPLICATOR

Angel Nunez Turnes, New York, N. Y.

Application July 26, 1945, Serial No. 607,129

5 Claims. (Cl. 132—88.7)

1

This invention relates to an applicator for a lip stain and has for an object to provide an automatic lip shaping tint applicator.

Another object of my invention is to provide a device for the application of either a flaccid waxy or liquid stain.

A further object of this invention is to provide a lipstick having the configuration of a pair of lips.

A still further object of the invention is to provide the combination of a lipstick and an applicator therefor, each conforming to the shape of a pair of lips.

Yet another object of my invention is to provide a lip tinting apparatus so formed that the tinting may be applied accurately without a mirror and in the dark when required.

Other features and advantages will become more readily apparent from the following description and the accompanying illustrative drawing in which:

Figure 1 is a perspective view of a lip tinting applicator.

Figure 2 is a similar view, the cover being removed,

Figure 3 is a side elevational view of the device,

Figure 4 is a top plan view of the applicator,

Figure 5 is a bottom plan view thereof,

Figure 6 is a sectional view taken on line 6—6 of Figure 4,

Figure 7 is a sectional view on line 7—7, Figure 4,

Figure 8 is a detail perspective view of a lipstick holder,

Figure 9 is a perspective view of a holder and liquid stain applicator.

In the accompanying drawing as above enumerated and in the following specification, like characters of reference indicate like parts throughout and in which 10, indicates my lip coloring device which consists of a plastic (or metal) case 11, having a removable bottom wall 12, and a removable top 13. The somewhat reduced in width ends 14 and 15, of the case are preferably formed solid with exception of bores 16 and 17, with longitudinal slots 18 and 19, extending into the interior 20, of the case and in reference to which more will be said later. Projecting from the upper surfaces 21 and 22, of said ends 14 and 15, are fingers 23 and 24, integral with said ends, and which project through slots 25 and 26, in said top 13. The edges 26' and 27, of the bowed center side wall portions 29 and 28, of the case, are shaped to the contour of a pair of fem-

2

inine lips. The bottom wall is provided with a central aperture 30.

Seated within the interior 20, of the case 11, is a lipstick actuating member 31, which is concavo-convex and to its convex surface 32, at the center thereof is a plastic (or other) push button 33, which normally projects through the opening 30, in the bottom wall of the case. On each side of the button 33, and formed integral with 10 the member 31, are a pair of fins 34 and 35, each terminating in extensions 36 and 37, which terminate in piston like members 38 and 39, operative with longitudinally split cylinders 40 and 41, and seating upon coil springs 42 and 43, seated 15 in the cylinders and adapted to press the members 38 and 39, normally to the wall 12, of the case whereby the button 33, is held outward of the case as clearly shown in Figure 6, of the drawing. The extensions 36 and 37, operate slidably 20 through the splits 44 and 45, of said cylinders and the slots 18 and 19, in the ends 14 and 15, of the case whereby the member 31, moves in a perfectly straight line, and without deviation from its course, the purpose of which will presently be 25 come obvious.

Seated within the concavity 46, of member 31, is a lipstick or waxy stain 47, shaped exactly to the desired contour or outline of a pair of female lips and conforming to the edges 26' and 27, of 30 the case 11, and is of the identical shape of the pad of Figure 8, which is to be referred to later. Concavities 48 and 49, formed in the outer wall surfaces 50 and 51, are for finger holds. Embedded in said walls 50 and 51, are the right-35 angular terminals 52 and 53, of spring clips 54 and 55, the rolled terminals 56 and 57, of which are adapted to spring over the end edges 58 and 59, of the top 13.

The member 31, is provided with an intermediate elongated flange 60, projecting from and integral with its concave surface 46, which flange is provided with apertures, through which the body portion of the lipstick 47, extends and whereby the same is held to its seat. The side walls 63 and 64, and their edges 65 and 66, are shaped to the contour of the sides and edges of the case 11. The fingers 23 and 24, are guides and to be placed in the corners of the mouth to correctly direct the wedge-shaped outer portion 67, of the lipstick 47, between the lips of the user in order that the projection 68, of the cupids bow formation of the edge 26', of the case and the similar outline 69, of side wall 70, of the lipstick may be correctly centered upon the upper lip of 55 the user. The fact that the mouth of different

users are of varying lengths will have no material effect in the use of my device as the user may easily contract the lips for engagement with both of said members 23 and 24, or on the other hand, the lips may be readily stretched lengthwise by them, and in any case the application of the tint will be correctly applied and centered and without the use of a mirror.

In Figure 9, of the drawing I illustrate a slight modification of the invention, in which is fixedly seated on the member 31, an absorbent pad 71, which is identical in configuration to the lipstick 47, and which may be periodically infused with a liquid lip stain and which is used in the same case and same manner.

It is thought that persons skilled in the art to which the invention relates will be able to obtain a clear understanding of the invention after considering the description in connection with the drawing. Therefore, a more lengthy description is regarded as unnecessary.

Changes in shape, size and rearrangement of details and parts such as come within the purview of the invention claimed may be resorted to, in actual practice, if desired.

Having now described my invention that which I claim as new and desire to procure by Letters Patent is:

1. In a device as described a lip-shaped case for applying a stain contained therein, a form for carrying the stain, said form being slidable and spring pressed in one direction, means for manual actuation thereof in the opposite direction, a removable bottom wall for the case, said means projecting through an aperture in said wall, means for centering the device upon the lips of the user, said centering means being integral with the walls of the case, a top for the case having apertures through which said centering means project, said stain being in plastic form, and having a cupid's bow outline.

2. In a device as described a lip-shaped case for applying a stain contained therein, a form for carrying the stain, said form being slidable and spring pressed in one direction, means for manual actuation thereof in the opposite direction, a removable bottom wall for the case, said means projecting through an aperture in said wall, means for centering the device upon the

5 lips of the user, said centering means being integral with the walls of the case, a top for the case having apertures through which said centering means project, and said stain being in plastic form.

10 3. In a device as described a lip-shaped case for applying a stain contained therein, a form for carrying the stain, said form being slidable and spring pressed in one direction, means for manual actuation thereof in the opposite direction, a removable bottom wall for the case, said means projecting through an aperture in said wall, means for centering the device upon the lips of the user, said centering means being integral with the walls of the case, and a top for the case having apertures through which said centering means project.

15 4. In a device as described a lip-shaped case for applying a stain contained therein, a form for carrying the stain, said form being slidable and spring pressed in one direction, means for manual actuation thereof in the opposite direction, a removable bottom wall for the case, said means projecting through an aperture in said wall, means for centering the device upon the lips of the user, and said centering means being integral with the walls of the case.

20 5. In a device as described a lip-shaped case for applying a stain contained therein, a form for carrying the stain, said form being slidable and spring pressed in one direction, means for manual actuation thereof in the opposite direction, a removable bottom wall for the case, said means projecting through an aperture in said wall, and means for centering the device upon the lips of the user.

ANGEL NUNEZ TURNES.
